UNITED STATES PATENT OFFICE.

MILTON B. HERBRICK, OF OMAHA, NEBRASKA.

CONCRETE BUILDING-SLAB.

1,394,550.

Specification of Letters Patent.

Patented Oct. 25, 1921.

Application filed September 22, 1920. Serial No. 412,037.

To all whom it may concern:

Be it known that I, MILTON B. HERBRICK, a citizen of the United States, residing at Omaha, in the county of Douglas and State of Nebraska, have invented certain new and useful Improvements in Concrete Building-Slabs, of which the following is a specification.

The present invention relates to building construction, and more particularly to reinforced concrete construction and slabs for use in the erection of buildings.

An object of the present invention is to minimize the cost of building construction; to save time and labor in such construction; and to provide slabs which may be manufactured at a point distant from the site of the building and which may be quickly and easily assembled.

Another object of the invention is to provide novel reinforcements for slabs which embody supporting features for joists and the like, and which provide interlocks between the slabs when assembled for holding the same in alinement and facilitating the anchoring of the slabs to each other and to a foundation or support.

A further object of the invention is to provide a novel form of reinforcing beam provided with seats or pockets adapted to receive the ends of joists for supporting the same and maintaining them in upright and properly spaced apart relation.

The above and various other objects and advantages of this invention will be in part described in, and in part understood from, the following detailed description of the present preferred embodiment, the same being illustrated in the accompanying drawings, wherein:

Figure 1, is a fragmentary sectional view of a corner of a building constructed according to the present invention.

Fig. 2, is a detail enlarged transverse section taken on the line 2—2 of Fig. 3 through a top reinforcement of one of the slabs employed.

Fig. 3, is a detail enlarged top plan view of the same.

Fig. 4, is a detail enlarged transverse section taken on the line 4—4 of Fig. 5, showing a bottom reinforcement for one of the slabs.

Fig. 5, is a top plan view of the same.

Fig. 6, is a detail transverse section taken on the line 6—6 of Fig. 7 showing a slightly modified form of the bottom reinforcement.

Fig. 7, is a top plan view of the same.

Fig. 8, is a detailed perspective view of a vertical edge reinforcement for the slab.

Referring to the drawings by numerals, 60 and first to Fig. 1, 10 designates a foundation or support which may be of brick or the like laid in the usual manner and providing an upper flat supporting surface.

The building is mainly composed of a 65 plurality of concrete slabs which are arranged in superposed relation and preferably with their adjacent ends meeting in offset or stepped relation to increase the stability of the walls. Each slab 11 may be 70 formed upon a flat table or platform and comprises a body of cementitious material reinforced by spaced apart rods 12 which are traversed by reinforcing wires 13 forming therewith a fabric. The latter, as shown 75 in Fig. 1, may be engaged in any suitable manner with the rods 12 to maintain the same in properly spaced relation and to thus insure the even distribution of stresses and strains throughout the body of the slab. 80

Each slab 11 is adapted to be disposed vertically and to rest at its lower end upon a subjacent slab or on the support 10 and is reinforced at its upper edge by a steel beam 14, shown in detail in Figs. 2 and 3. 85 In cross-section each beam 14 is substantially C-shape and provided with a depending flange 15 the top edge adapted to over-lie the outer face of the slab 11 and provided with outwardly stamped lugs or 90 projections 16 for supporting a facing 17 of a plastic or other suitable composition. The beam 14 projects downwardly against the inner side of the slab 11 to an appreciable extent and has at its lower edge an inturned 95 flange 18 embedded in the slab and forming a rest as will appear. The inner side of the beam 14 is provided with suitably spaced apart recesses or pockets 19 into which are adapted to be inserted the ends of girders 100 or beams 20 for supporting flooring and the like, and the pockets 19 terminate at their bottoms in the flange 18, the latter forming a ledge or support for the ends of the girders 20. The beam 14 also has a plurality of 105 outstanding ears 21 adapted to lie against the opposite sides of the girders 20 and are apertured, as at 22, to receive nails or the like for holding the ends of the girders in the pockets 19.

The bottom edges of the slabs are reinforced by beams 23, shown in detail in Figs.

4 and 5. Each beam 23 comprises a flat body portion adapted to lie against the lower edge of the slab and is provided along opposite edges with spaced apart upstanding projections 24 adapted to embrace the opposite sides of the slab 11 and having at such edges spaced apart depending projections 25 adapted to embrace the opposite sides of a subjacent slab 11 for anchoring the slabs to each other and in true vertical alinement. The outer projections 24 preferably have spurs 26 outstanding therefrom adapted to further hold the facing layer 17 against the outer side of the slab. These bottom reinforcing beams 23 are provided with key-hole slots 27 in the body part thereof and at spaced intervals for receiving therethrough the vertical reinforcing wires 18, the latter being threaded through the larger ends of the slots and wedged into the smaller ends thereof for binding the wires in place.

As a modification, the slabs 11 which are adapted to be placed directly upon the support 10 are provided with a bottom reinforcing beam 28 such as is shown in Figs. 6 and 7. This type of beam has the flat body portion adapted to lie flat upon the support 10 and has upstanding projections 29 for embracing the opposite faces of the slab 11 and is provided at its outer side with the outwardly struck spurs 30. The inner edge of the beam 28 has a horizontally projecting lug or ear 31 adapted to lie upon the upper face of the support and to extend inwardly from the slab and to receive fastening devices 32 for securing the lower slab to the support.

The ends of the slabs are reinforced by vertical end beams 33 shown in Fig. 8. These beams are substantially W-shape in cross-section and have lateral flanges 34 which are off-set from the edges of the body of the beam and the body is adapted to be positioned in the slab with the edges of the flanges extending inwardly and preferably lying flush with the opposite sides of the slab.

The slabs are erected with their adjacent ends in spaced apart relation, as shown in Fig. 1, and a cementitious filler 35 is adapted to be poured or otherwise suitably placed between the adjacent end beams 33 for completing the wall and for anchoring the end beams 33 together.

Where openings, such as windows and doors, are to be formed in the wall, the corresponding slabs 11 may be molded with frames 36 of channel iron or the like, in the slabs, and defining the proportions and sizes of such openings. Joists and ceiling beams may be conventionally placed in the building structure and in such cases the present invention contemplates the use of the reinforcing channel beams 37 at the

tops of the slabs as shown in Fig. 1. The top slabs 11 may be provided with upstanding bolts 38 anchored in the cementitious body of the slabs for securing plates 39 to the top of the wall for receiving the heels 70 of rafters or the like in roof construction.

It is apparent from the above that the slabs 11 may be individually molded or formed at a factory and shipped to the building site. Also, that the slabs are reinforced internally by the rods and wires 12 and 13 and are reinforced at their top, bottom and lateral edges to protect the same, not only during shipment and handling, but also against cracking, temperature changes 80 and weights and stresses imposed on them incident to erection and use.

It will further be noted that the peculiar construction of the top reinforcing beams 14 is such that the girders 20 or the like 85 may be properly held in upright position and also suitably supported upon the embedded flange or ledge 18. The general structure is such that the slabs may be standardized in size and form and may be used 90 as units with which various sizes and types of buildings may be quickly and easily erected.

It is of course understood that various changes and modifications may be made in 95 the details of construction, size, proportion and materials used, without departing from the spirit of this invention, such modifications and changes being restricted only by the scope of the following claims.

What is claimed is:

1. In building construction, a plurality of slabs adapted to be placed in edgewise superposed relation, each slab having top and bottom reinforcements embedded therein 105 and with spaced apart recesses in the inner side of the top reinforcements for the reception of the ends of girders, said bottom reinforcements having projections thereon adapted to interlock over the top reinforcements of subjacent slabs when the latter are 110 assembled, said slabs also having edge reinforcements adapted to support and protect the lateral edges of the slabs.

2. A slab for building construction comprising a cementitious body, a top reinforcement molded in the upper edge of the slab and having recesses therein and said body having therein corresponding recesses for the reception of the ends of girders of a 115 building, and a bottom reinforcement embedded in the lower edge of the slab and having projections adapted to interlock with the opposite sides of the top reinforcement of the sub-jacent slab.

3. A slab for building construction including a flat cementitious body, a beam embedded in the upper edge of the body and having an inwardly extending flange overlapping the outer face of the slab and hav- 130

ing an inwardly extending portion overlapping the inner face of the slab and with an inwardly projecting portion forming a ledge at the inner face of the slab, said beam also having recesses therein opening through the top of the beam and extending to said ledge for the reception of the ends of girders to retain the same on the ledge.

4. A slab for building construction including a flat cementitious body, crossed reinforcements embedded in the body, beams embedded in the edges of the body, certain of said beams having openings therein for the reception of said first reinforcements and said openings having reduced portions into which said reinforcements are adapted to be wedged for holding the reinforcements in position, one of said beams having recesses therein forming seats for receiving and holding the ends of girders and the other beam having interlocking portions adapted to engage the reinforcing beam of an adjacent slab.

5. A slab for building construction including a flat cementitious body and a **C**-

shaped beam embedded in the upper edge of the body and provided with uniformly spaced apart recesses forming pockets in the beam for receiving the ends of girders, the lower lip of said beam forming the bottoms 30 of the pockets and providing an embedded ledge for supporting said girders.

6. A slab for building construction comprising a cementitious body, and a **C**-shaped beam embedded in the top of the body and 35 having recesses in its intermediate portion extending from the lower lip of the beam through the top thereof and forming pockets to receive the ends of girders adapted to be supported upon said lower lip, said beam also having outstanding projections at opposite sides of the recesses adapted to be secured to the sides of the girders for holding the same in the pockets.

In testimony whereof, I have affixed my 45 signature in presence of two witnesses.

MILTON B. HERBRICK.
